CABLE CLAMP

John J. Taylor, Wadsworth, Ohio, assignor to
The Ohio Brass Company, Mansfield, Ohio, a
corporation of New Jersey

Application July 12, 1935, Serial No. 30,989

12 Claims. (Cl. 24—135)

This invention relates to clamps for holding electrical conductors or other flexible strands, and has for one of its objects the provision of a conductor clamp which shall be light and strong and which shall effectively grip the conductor so as to utilize the maximum strength of the conductor.

A further object of the invention is to provide a conductor clamp which is adaptable to conductors of various sizes and which will effectively hold the different sized conductors.

10 Another object of the invention is to provide a clamp which is convenient to install, economical to manufacture and efficient in operation.

15 Other objects and advantages will appear from the following description.

The invention is exemplified by the combination and arrangement of parts shown in the accompanying drawing and described in the following specification, and it is more particularly pointed out in the appended claims.

In the drawing:

Fig. 1 is a side elevation of a conductor clamp embodying one form of the present invention.

20 Fig. 2 is a view looking in the direction of the arrows 2—2 of Fig. 1.

Fig. 3 is a fragmentary view looking in the direction of the arrows 3—3 of Fig. 1.

25 Fig. 4 is a section on line 4—4 of Fig. 3.

30 The numeral 10 designates generally the main body of the clamp having a curved conductor seat 11 which is V-shaped in cross section and which gradually increases in curvature from the point of entrance of the taut end of the cable at 12 to the exit point of the slack end at 13. The seat 11 lies in the plane of the cable from the entrance point 12 to a point 14, at which point the seat curves laterally as indicated by the line 15 in Fig. 3. The seat 15, as will be seen from this figure, curves first to one side and then back to the original plane of the cable. A keeper piece 16 is provided with a convexly curved seat portion 17 which cooperates with the seat portion 15.

35 The seat portions 15 and 17 are both grooved in cross section, as shown in Fig. 4, so as to grip the cable. The keeper 16 is provided with two grooves 17 and 19 at opposite sides thereof. The keeper 16 may be reversed by swinging it about its clamping bolt 20 so as to bring either of the grooves 17 or 19 into registration with the groove 15. Both of these grooves are curved longitudinally, as shown in Fig. 3, to conform to the curvature of the seat 15. The groove 17 is formed in the top of a ridge on the keeper 16 so that it

may cooperate closely with the groove 15, as shown in Fig. 4.

The body portion of the clamp is provided with a fulcrum 21 at the side of the bolt 20 opposite from the groove 15 so that when the nut 22 is 5 screwed down on the bolt 20 the keeper piece will swing about the fulcrum 21 to clamp the cable against the seat 15. The bearing for the nut 22 is slightly rounded, as shown at 23, to permit the nut to accommodate itself to various positions of 10 the keeper 16 upon its fulcrum 21. The bolt 20 fits sufficiently loosely in the opening through the keeper 16 to permit the keeper to rotate upon its fulcrum 21 a sufficient distance to grip conductors of various sizes against the seat 15. For 15 larger sized conductors the seat 19 is moved into registration with the seat 15 and for smaller sized conductors the seat 17 cooperates with the seat 15, as shown in Fig. 4.

In Fig. 2 the keeper is in a reversed position 20 from that of Fig. 4 with the larger groove 19 in registration with the groove 15. The lateral curvature in the clamping seat for the cable provides a continuation of the snubbing action of the seat 11 entirely through to the exit end of 25 the cable seat and thus supplements the gripping action of the keeper piece 16 in holding the end of the cable. By utilizing the gripping seat curved laterally out of the plane of the cable and then back into the plane, the loose end of the cable 30 is directed to one side of the plane of the cable without producing a turning moment on the cable clamp, as is the case where the cable is spirally wound on a drum or the cable seat is given a spiral form to throw the loose end to one 35 side of the plane passing through the taut end of the cable.

By providing a keeper piece having a fulcrum at one side of the clamping bolt and a clamping 40 groove at the other, a single clamping bolt can be used passing through an intermediate opening. This is a much simpler construction than an arrangement in which the clamping piece is held on by U-bolts or J-bolts because in the arrangement 45 shown a standard square shank bolt can be used which is much cheaper than specially formed U-bolts or J-bolts. Furthermore, a simpler keeper piece is provided which can be readily reversed so that cables of a larger range of diameters can 50 be held by the same clamp. It is unnecessary to separate entirely the parts of the clamp in order to reverse the keeper piece. All that is required is to back the nut off a short distance and then the keeper piece can be rotated to bring either 55

of its gripper seats into registration with the clamp seat.

The V-groove in the clamp body will of course accommodate cables of a large range of diameter. 5 The seat 15 is made large enough for the largest cable for which the device is designed and the notch 17 in the keeper piece can be brought close to the central portion of the seat 15 because of the ridge upon which the notch 17 is mounted, 10 the ridge being sufficiently narrow to extend partially into the notch 15. The clamp may be secured to a suitable support by means of ears 24 and a pin 25.

The parts may be made of malleable iron and 15 are readily cast without extensive or difficult coring operations. No machining is required and the clamping bolt being of standard form may be purchased on the market very cheaply so that the entire device is very economical to manufacture and is light and strong and of substantially 20 universal application to cables of a considerable range in size.

I claim:

1. A clamp for holding a loaded cable and for 25 receiving the force of the load thereon so that the portion of the cable extending from said clamp at one side thereof will be drawn taut by the load and the other end of the cable will be slack, said clamp having a seat of gradually 30 increasing curvature from the taut end of the cable toward the slack end thereof, a portion of said seat being co-planar with the taut end of the cable held thereby while another portion of said seat is curved laterally out of the plane defined 35 by the taut end of the cable and the first mentioned portion of said seat, said laterally curved portion lying in a plane substantially normal to said first named plane.

2. A clamp for holding a loaded cable and for 40 receiving the force of the load thereon so that the portion of the cable extending from said clamp at one side thereof will be drawn taut by the load and the other end of the cable will be slack, said clamp having a seat of gradually 45 increasing curvature from the taut end of the cable toward the slack end thereof, a portion of said seat being co-planar with the taut end of the cable held thereby while another portion of said seat is curved laterally out of the plane defined 50 by the taut end of the cable and the first mentioned portion of said seat, said laterally curved portion lying in a plane substantially normal to said first named plane and a keeper cooperating with said laterally curved portion of said seat 55 for gripping the cable adjacent its slack end.

3. A clamp for holding a loaded cable and for receiving the force of the load thereon so that the portion of the cable extending from said clamp at one side thereof will be drawn taut by 60 the load and the other end of the cable will be slack, said clamp having a curved seat about which the cable is directed, a portion of said seat being co-planar with the taut end of the cable while another portion of said seat curves laterally 65 to one side of the plane defined by said first named portion and back substantially into said plane, and means cooperating with said laterally curved portion for gripping the cable adjacent its slack end.

70 4. A clamp for holding a loaded cable and for receiving the force of the load thereon so that the portion of the cable extending from said clamp at one side thereof will be drawn taut by the load and the other end of the cable will be 75 slack, said clamp comprising a curved seat for

receiving a cable, a portion of said seat being co-planar with the taut end of the cable and another portion of said seat being curved laterally relative to the plane of said first named portion in an arc, the ends of which are substantially 5 in said plane, and a keeper cooperating with said laterally curved portion for gripping the cable adjacent its slack end.

5. A clamp for holding a loaded cable and for receiving the force of the load thereon so that 10 the portion of the cable extending from said clamp at one side thereof will be drawn taut by the load and the other end of the cable will be slack, said clamp having a cable seat thereon which increases in curvature from the taut end 15 of the cable toward the slack end thereof, said seat having a laterally curved portion adjacent the slack end of the cable said laterally curved portion lying in a plane transverse to the plane of the remaining portion of said seat. 20

6. A cable clamp having a seat for receiving the cable, a portion of said seat being curved and having a radial bearing for said cable and another portion of said seat being curved in a plane transverse to the plane of said first named 25 portion and having a lateral bearing for the cable, and a keeper for gripping the cable against said lateral bearing portion.

7. A cable clamp having a curved radially bearing seat, the curvature of which gradually 30 increases from its entrance portion, said seat also having a laterally bearing portion adjacent the slack end of the cable, said laterally bearing portion being curved laterally away from the plane of said radially bearing portion and lying 35 in a plane transverse to the plane of said radially bearing portion, and a keeper for pressing the cable against said laterally bearing portion.

8. A clamp for holding a loaded cable and for receiving the force of the load thereon so that the 40 portion of the cable extending from said clamp at one side thereof will be drawn taut by the load and the other end of the cable will be slack, said clamp having a curved, radially bearing seat portion of increasing curvature from the taut 45 end of the cable toward the slack end thereof, and a laterally bearing seat portion adjacent the slack end of the cable, said laterally bearing seat portion being curved in an arc, the plane of which is transverse to the plane of said radially bearing portion and the ends of which lie substantially in the plane of said radially bearing portion while the central portion is displaced from said plane, and a keeper for gripping the cable against said laterally bearing portion. 55

9. A cable clamp comprising a curved radially bearing seat portion and a laterally bearing seat portion, a keeper for gripping the cable against said laterally bearing seat portion, a fulcrum for said keeper displaced from said laterally bearing 60 seat portion, and a bolt extending in a direction transverse to the plane of said curved radially bearing seat portion through said keeper between said fulcrum and said laterally bearing seat portion for pressing said keeper toward said 65 laterally bearing seat portion for exerting pressure on a cable in said laterally bearing seat portion in a direction transverse to the plane of said curved radially bearing seat portion.

10. A cable clamp comprising a snubbing seat 70 and a gripping seat, said gripping seat having a bearing face disposed at one side of the plane of said snubbing seat and a reversible gripper having cable engaging portions at opposite sides thereof, a bolt extending through said gripper 75

for selectively holding either of said cable engaging portions in registration with said gripper seat, and a fulcrum for supporting the cable engaging portion of said gripper not cooperating with said cable engaging seat.

5 11. A cable clamp comprising a snubbing seat, a keeper for holding a cable in said seat, said keeper having a pair of spaced cable engaging grooves of different sizes to fit different size cables, a fulcrum for said keeper spaced away from said cable seat, and gripping means for pressing said keeper toward said seat and fulcrum, said gripper means cooperating with said clamp between said seat and fulcrum and with 10 said keeper between said grooves, said keeper being reversible to bring either cable engaging groove into registration with said seat while the other cable engaging groove registers with said fulcrum.

12. A cable clamp comprising a main body portion having a longitudinally curved cable seat thereon, a keeper plate for gripping a cable in said seat, said keeper plate having spaced longitudinally curved cable engaging grooves of different sizes at the opposite edges thereof, a fulcrum on said body portion spaced from said seat for supporting said keeper plate, and a bolt extending through said body portion between said seat and fulcrum and through said keeper 15 plate between said grooves for pressing said keeper plate toward said body portion, said keeper plate being reversible to bring either groove thereon into registration with said seat while the other groove engages said fulcrum. 15
